TRI-COLOR KINESCOPE BEAM CONVERGENCE SYSTEM

Morris D. Nelson, Bronx, N. Y., assignor to Radio Corporation of America, a corporation of Delaware

Application July 1, 1953, Serial No. 365,331

9 Claims. (Cl. 315—13)

This invention relates to systems for controlling the electron beam energy of cathode ray tubes. It pertains particularly to the control of a plurality of electron beam components used in television kinescopes so as to effect substantial convergence of the beam components at all points of a raster scanned at a target electrode.

One type of cathode ray tube in which there is encountered the problem of maintaining substantial convergence of a plurality of beam components at a target electrode is a color kinescope such as that disclosed in a paper by H. B. Law titled "A three-gun shadow-mask color kinescope" published in the Proceedings of the I. R. E., vol. 39, No. 10, October 1951 at page 1186. Such a tube has a luminescent screen consisting of a multiplicity of phosphor areas of sub-elemental dimensions. Different ones of the phosphor areas are capable of producing light of the component image colors when excited by electron beam energy. In this tube, the different light-producing phosphor areas are excited respectively by a plurality of electron beams, or by a plurality of components of a single beam, approaching the screen from different angles through an apertured electrode. Color selection is secured by the angle at which the electron beam components approach the screen. A tube of the kind described forms the subject matter of U. S. Patent 2,595,548 granted May 6, 1952, to Alfred C. Schroeder for "Picture Reproducing Apparatus."

The expression "electron beam components" as used in this specification and claims will be understood to denote the phosphor-exciting electronic energy produced either by a single, or by a plurality of, electron guns. This energy may be continuous or pulsating as required without departing from the scope of the invention. An example of a color kinescope in which different components of a single electron beam are used to excite a phosphor screen of the kind described is disclosed in a paper by R. R. Law, titled "A one-gun shadow-mask color kinescope" published in the Proceedings of the I. R. E., vol. 39, No. 10, October 1951, at page 1194. Such a tube forms the subject matter of a copending U. S. application of Russell R. Law, Serial No. 165,552, filed June 1, 1950 and titled "Color Television."

The successful operation of a multi-color kinescope of the type referred to requires that the plurality of electron beam components be made to converge substantially at the apertured electrode at all points in the scanned raster. In view of the fact that the different points of such a target electrode are at different distances from the point or region of the electron beam deflection, it is necessary to provide a field-producing means which is variably energized to produce the desired dynamic convergence control. One such electron beam control system is disclosed in a paper by Albert W. Friend titled "Deflection and convergence in color kinescopes" published in the proceedings of the I. R. E., vol. 39, No. 10, October 1951 at page 1249. Such a system forms the subject matter of a copending U. S. application of Albert W. Friend, Serial No. 164,444, filed May 26, 1950 and titled "Electron

2

Beam Control System." In the system proposed by Friend, electron-optical apparatus is energized both statically and dynamically to produce the desired result. By means including the static energization of the electron-optical apparatus, the Friend system effects initial convergence of the electron beam components substantially at the center of the raster to be scanned. The dynamic energization of the electron-optical apparatus is effected as

5 functions of both the horizontal and vertical beam deflection. Ideally these functions are parabolic. However, it is somewhat difficult to produce the ideal energizing waveforms, particularly at the vertical deflection frequency.

10 Therefore, it is an object of this invention to provide improved and simplified apparatus by which to develop waveforms for the dynamic energization of an electron beam-controlling system for a multi-beam kinescope.

Another object of the invention is to provide improved apparatus by which to develop, directly from the 15 deflection apparatus, waveforms for effecting dynamic convergence of the electron beam components of a multi-beam kinescope.

In accordance with this invention, there is provided a 20 convergence control wave-generating apparatus including a wave-shaping network having a plurality of branches. Oppositely phased, substantially similar sawtooth waves at one of the deflection frequencies are impressed upon two 25 constituent wave branches of the network. The network also includes an integrating branch which is coupled to at least one of the constituent wave network branches so as to produce a substantially parabolic wave which may be derived from the integrating network branch. The 30 integrating network branch may be coupled to both constituent wave network branches in a manner to combine either polarity of a sawtooth wave with the parabolic wave. The convergence control wave thus produced is 35 basically of parabolic form and may have a sawtooth component if desired.

The novel features that are considered characteristic 40 of this invention are set forth with particularity in the appended claims. The invention itself, however, both as to its organization and method of operation, as well as additional objects and advantages thereof, will best be 45 understood from the following description when read in connection with the accompanying drawings.

In the drawings:

Figure 1 is a block diagram of a representative form 50 of apparatus with which the present invention may be employed;

Figure 2 is a schematic circuit diagram of an illustrative 55 form of a convergence control wave-generating apparatus in accordance with the invention; and,

Figure 3 shows a series of curves illustrating different kinds of convergence control waveforms which may be 60 produced by apparatus in accordance with the invention.

Reference first will be made to Figure 1 of the drawings for a description of an illustrative embodiment of the invention. The television receiver represented in this figure is generally conventional and includes an antenna 11 to which is coupled a conventional television signal receiver 12. It will be understood that the receiver 12 may include such usual apparatus as carrier wave amplifiers at both radio and intermediate frequencies, a frequency converter and a carrier wave demodulator or signal detector. Accordingly, it will be understood that there are derived from the receiver 12 the video and synchronizing signals. The video signals derived from the receiver 12 are impressed upon a video signal channel 13 and the synchronizing signals are impressed upon a sync signal separator 14. The video signal channel is coupled to the usual electron beam control apparatus, customarily

referred to as electron gun apparatus, of an image-reproducing device such as a kinescope 15.

In the illustrative embodiment of the invention, it is assumed that the invention is used in a color television system. In this case, the kinescope is of the same general type disclosed in the H. B. Law paper previously referred to. It will be understood, however, that the kinescope alternatively may be of other types such as that shown in the aforementioned R. R. Law paper. In either case, however, the kinescope has a substantially flat luminescent screen 16 which is provided with a multiplicity of small phosphor areas arranged in groups and capable respectively of producing light of the different primary colors in which the image is to be reproduced when excited by electron beam energy. In back of, and spaced from the screen 16, there is an apertured masking electrode 17 having an aperture for, and in alignment with, each group of phosphor areas of the screen 16. In the particular tube illustrated, the kinescope also has a plurality of electron guns 18, 19 and 20, equal in number to the number of primary colors in which the image is to be reproduced. As previously indicated, these three electron guns are coupled to the video signal channel 13 for respective control by video signals representing the three primary colors in which the image is to be reproduced. It will be understood that each of these guns may be conventional consisting of a cathode, a control grid, and a first anode, or beam-forming electrode. Also associated with the three electron guns are corresponding individual beam-focusing anodes 22, 23 and 24. The three electron guns 18, 19 and 20, together with their associated focusing electrodes 22, 23 and 24 respectively, function to develop respective electron beams 25, 26 and 27 which are caused to approach the target electrode structure, including the luminescent screen 16 and the masking electrode 17, from three different angles which, for convenience, have been shown greatly exaggerated in the drawing. By means of the different angles of approach these beams are caused to excite the different colored light-producing phosphors.

The color kinescope 15 additionally is provided with an electro-static type of beam-converging apparatus which includes a convergence anode 28 located adjacent the paths followed by the electron beams in the predeflection region. The kinescope also includes the usual final, or beam-accelerating, anode 29 generally in the form of a wall coating substantially as shown and extending from the predeflection region adjacent to the convergence anode 28 to the vicinity of the target electrode structure including the screen 16.

The different static potentials which are impressed upon the various kinescope electrodes are derived from a power supply 31, across the terminals of which is connected a voltage divider resistor 32. The various electrode potentials are derived by making suitable connections to the voltage divider resistor generally in the manner shown. The individual beam-focusing electrodes 22, 23 and 24 are connected together with and to a relatively low positive potential point on the voltage divider resistor 32. The convergence anode 28 is coupled to a somewhat higher positive potential point of the resistor 32 so that, as a result of the potential difference between it and the individual beam focusing anodes 22, 23 and 24, there are produced electrostatic electron-optical lenses by which individual beam focusing is effected. In a like manner, the final anode 29 is connected to a relatively high positive potential point on the voltage divider resistor 32 so as to create another electron-optical lens with the convergence anode 28. The purpose of this latter electron-optical device is to produce the desired convergence of the individual electron beams substantially in the plane of the apertured electrode 17.

The color kinescope 15 also is provided with apparatus by which to deflect the plurality of electron beam components both vertically and horizontally to scan the usual raster at the luminescent screen 16. In this embodiment of the invention the deflection apparatus includes a yoke 33 which in general is of a conventional type. It

consists of a pair of interconnected coils forming a horizontal deflection winding and another pair of coils forming a vertical deflection winding. The yoke is mounted around the neck of the kinescope in the region adjacent to the point at which the neck joins the conical section of the tube. The horizontal and vertical windings of the yoke 33 are energized by substantially conventional apparatus. The sync signal separator 14, which separates the sync signals from the video signals and from one another, produces horizontal and vertical frequency sync signals respectively in its output circuits H and V. The horizontal output circuit H is coupled to a horizontal sweep oscillator 34, the output of which, in turn, is coupled to the input circuit of a horizontal sweep output apparatus 35. Both of these horizontal sweep components may be entirely conventional. The output circuit of the horizontal sweep output apparatus 35 is coupled to the horizontal deflection winding of the yoke 33 in the customary manner.

The vertical sync separator output circuit V is coupled to a vertical sweep oscillator 36 which produces at its output terminal 37 a substantially sawtooth deflection wave 38 at the vertical deflection frequency. The output of the vertical sweep oscillator is coupled to the input circuit of a vertical sweep output stage 39 having an output terminal 40 at which a sawtooth deflection wave 41 is developed. The output circuit of the vertical sweep output apparatus is connected to the vertical deflection winding of the yoke 33.

In order to effect the desired convergence of the electron beam components of the tri-color kinescope 15 at both horizontal and vertical deflection frequencies, a substantially sawtooth wave 42 at horizontal deflection frequency is impressed upon a horizontal convergence control wave generator 43. This apparatus may be substantially of the type disclosed in the Friend paper previously referred to. However, if desired, it may be of the same general type, with suitable modifications for the particular operating frequency, as a generator in accordance with the present invention. In any case, it will be understood that the horizontal convergence control wave generator functions to produce a substantially parabolic convergence control wave 44 at the horizontal deflection frequency. Such a wave is impressed upon the primary winding 45 of a convergence control wave output transformer 46. The secondary winding 47 of this output transformer is coupled by means including the capacitor 48 to the convergence control anode 28 of the tri-color kinescope 15.

The substantially sawtooth deflection wave 38 and 41 at vertical deflection frequency derived respectively from terminals 37 and 40 are impressed upon input terminals 49 and 50 of a vertical convergence control wave generator 51. An illustrative form of this generator is in accordance with the present invention and will be described in detail presently. It will be understood that the vertical convergence control wave generator 51 functions to produce a substantially parabolic wave 52 at an output terminal 53. This wave is combined with the convergence control wave 44 at the horizontal deflection frequency by coupling the terminal 53 to the secondary winding 47 of the output transformer 46.

Reference now will be made to Figure 2 of the drawings for a description of an illustrative form of the present invention. The substantially sawtooth deflection wave 38, which is developed at the output terminal 37 of the vertical sweep oscillator for employment as the driving voltage for the vertical sweep output 39, usually is developed across such a circuit as one including a resistor 54 and a capacitor 55. The deflection wave 38 includes a sawtooth component 56 and a peaking component 57. The peaking component is developed across the resistor 54 and the sawtooth component is developed

across the capacitor 55. By coupling to the capacitor 55, only the sawtooth component 56 of the deflection wave 38 is impressed upon a capacity type of voltage divider including capacitors 58 and 59. By means of such an arrangement, an adjustment of one circuit does not disturb the operation of another one of the circuits coupled to the output of the vertical sweep oscillator 36 of Figure 1. In this manner, a sawtooth wave 60 is impressed upon the input circuit of a triode electron tube 61. The input sawtooth wave 60 is converted by means including this tube into an output constituent sawtooth wave 62 of negative polarity. It also is to be noted that the reformed constituent wave 62 does not include the peaking pulses of the deflection sawtooth wave 38.

The vertical sweep output apparatus includes an electron tube 63 which functions in the usual manner to couple the substantially sawtooth wave 38 to the output terminal 40 by means including an output transformer 64. As indicated in this figure and also in Figure 1, the substantially sawtooth wave 41 so developed is impressed upon the deflection yoke 33 of the tri-color kinescope 15 of Figure 1.

The deflection sawtooth wave 4 which is impressed upon the input terminal 50 of the vertical convergence control wave generator 51 of Figure 1 has the peaking component clipped therefrom by means including a unilaterally conducting device such as a crystal diode 65 connected in series with the anode supply voltage for the tube 61, resistors 66 and 67 and a capacitor 68. By such means, there is impressed upon one terminal of a signal mixing potentiometer 69 a substantially reformed constituent sawtooth wave 70 of positive polarity. As previously described, the negative constituent sawtooth wave 62 is impressed by means including a series resistor 71 upon the other terminal of the potentiometer 69.

There also is connected in parallel with the series arrangement of the potentiometer 69 and the resistor 71 another potentiometer 72 across which there is developed a sawtooth wave which is integrated by means including the potentiometer 72, a resistor 73 and a capacitor 74, whereby to produce a substantially parabolic wave 75 which is impressed upon the input circuit of an output tube 76. The potentiometers 69 and 72, together with such other apparatus as the resistor 69 and the capacitor 70, comprise a wave-shaping network. Accordingly, the substantially parabolic wave 52 is developed at the output terminal 53.

The interconnection of the potentiometers 69 and 72 by means of the circuit which includes the integrating network comprising the resistor 73 and the capacitor 74 enables a suitable mixture of the sawtooth and parabolic wave components to produce the desired convergence control wave. The amplitude of such a wave, which is essentially parabolic, is controlled by means of the potentiometer 72. An adjustment of the potentiometer 69 effects the combination with the parabolic wave of a sawtooth wave component of either polarity and of any desired amplitude. Such a facility is seen to be available by virtue of the fact that the constituent sawtooth waves 62 and 70 respectively of opposite polarity are impressed upon opposite terminals of the potentiometer 69 as described.

In order to avoid the use of a convergence control wave output transformer for the purpose of producing a convergence control wave of sufficient amplitude, the anode of the convergence control wave output tube 76 is provided with a suitable voltage supply by a connection to a voltage divider or bleeder network including a series connection of resistors 77, 78 and 79 connected between terminals 80 and 81. There is impressed upon the terminal 80, for example, a potential of approximately 700 volts which may be conveniently derived from the boosted "B" supply usually available in the horizontal deflection output circuit. Such a power supply is commonly used and may be in accordance with

the system shown in U. S. Patent 2,598,134 granted May 27, 1952, to O. H. Schade and titled "Power Conservation System." The terminal 81 may also have impressed thereon a higher positive potential of the order of 3500 volts, for example. Such a voltage may be provided somewhat in the usual manner by means of a flyback high voltage power supply such as that shown in U. S. Patent 2,074,495 granted March 23, 1937, to A. W. Vance and titled "Circuits for Cathode Ray Tubes." It has been determined that the point on the voltage divider to which the anode of the tube 76 is connected has a voltage of approximately 1300 volts when the tube 76 is cut off. During the intervals of current conduction in the tube 76, the anode voltage may drop to approximately ground potential because of the relatively large value of the load resistance which, in the circuit indicated in the drawing, is effectively 1.8 megohms. As indicated, the resistor 79 of the voltage divider may be in the form of a potentiometer, the adjustable contact of which is connected to the focusing anodes such as 22, 23 and 24 of Figure 1, as indicated.

Figure 3 illustrates three typical types of convergence control waveforms which may be obtained by use of apparatus such as that described embodying the invention. The wave 82 is one which is substantially all parabolic in form. The setting of the potentiometer 69 is such that no sawtooth wave component is included. The wave 83 is one which is made up of a parabolic component such as the wave 82 to which is added a sawtooth wave component of positive polarity. The wave 84 is a parabolic wave to which a negative sawtooth component has been added. It is seen that the wave 82 is of a symmetrical form in any one cycle thereof, whereas the wave 83 is effectively tipped toward the left, as viewed in the drawing, and the wave 84 is tipped toward the right.

Thus, it may be seen that the present invention provides apparatus of a relatively simple character which materially reduces the cost of equipment necessary to generate a beam convergence control wave. It is seen that such apparatus requires only a resistance coupled amplifier which may be operated from the available B+ supply. It, therefore, is unnecessary to employ an output transformer for the purpose of increasing the amplitude of the convergence control wave. Not only is such transformer apparatus relatively costly, particularly for operation at field deflection frequency, but also it tends to distort the convergence control waves from the desired form, thereby requiring additional apparatus by which to compensate for such distortion.

Having described an illustrative embodiment of the invention, its scope is pointed out in the appended claims.

What is claimed is:

1. In a cathode ray image reproducing system wherein a plurality of electron beam components, which traverse predeflection paths that are spaced respectively about the longitudinal axis of a tube, are angularly deflected both horizontally and vertically to scan a raster and having field-producing means adjacent to said predeflection paths and energizable to effect substantial convergence of said beam components at all points of said raster, a system to energize said field-producing means comprising, a convergence control wave-shaping network including a plurality of branches, means to produce first and second constituent sawtooth waves of opposite polarity and having one of said deflection frequencies, means coupling said constituent wave-producing means to said wave-shaping network in a manner to impress said first and second constituent sawtooth waves respectively upon two constituent wave branches of said network, means including an integrating branch of said network coupled to one of said constituent wave network branches to integrate one of said constituent sawtooth waves into a substantially parabolic waveform, and means coupled to said integrating network branch to derive therefrom said convergence control wave for application to said field-producing means,

2. In a cathode ray image reproducing system wherein a plurality of electron beam components, which traverse predeflection paths that are spaced respectively about the longitudinal axis of a tube, are angularly deflected both horizontally and vertically to scan a raster and having field-producing means adjacent to said predeflection paths and energizable to effect substantial convergence of said beam components at all points of said raster, a system to energize said field-producing means comprising, a source of a substantially sawtooth raster-scanning deflection wave, a convergence control wave-shaping network including a plurality of branches, means coupled to said sawtooth wave source to produce first and second constituent sawtooth waves of opposite polarity and generally similar in shape to said deflection wave, means coupling said constituent wave-producing means to said wave-shaping network in a manner to impress said first and second constituent sawtooth waves respectively upon two constituent wave branches of said network, means including an integrating branch of said network coupled between said two constituent wave network branches to integrate one of said constituent sawtooth waves into a substantially parabolic waveform, and means coupled to said integrating network branch to derive therefrom said convergence control wave.

3. In a cathode ray image reproducing system wherein a plurality of electron beam components, which traverse predeflection paths that are spaced respectively about the longitudinal axis of a tube, are angularly deflected both horizontally and vertically to scan a raster and having field-producing means adjacent to said predeflection paths and energizable to effect substantial convergence of said beam components at all points of said raster, a system to energize said field-producing means comprising, a source of a substantially sawtooth raster-scanning deflection wave, a convergence control wave-shaping network including two branches, means coupled to said sawtooth wave source to produce a first constituent sawtooth wave of predetermined polarity and generally similar in shape to said deflection wave, means coupling said first constituent wave-producing means to said wave-shaping network in a manner to impress said first constituent sawtooth wave upon both of said network branches, means coupled to said deflection wave source to produce a second constituent sawtooth wave similar in shape to said first constituent sawtooth wave but of opposite polarity, means coupling said second constituent wave-producing means to said wave-shaping network in a manner to impress said second constituent sawtooth wave upon both of said network branches, means coupled between said network branches in a manner to integrate one of said constituent sawtooth waves into a substantially parabolic waveform, and means coupled to said wave-shaping network to derive therefrom said convergence control wave for application to said field-producing means.

4. In a cathode ray image reproducing system wherein a plurality of electron beam components, which traverse predeflection paths that are spaced respectively about the longitudinal axis of a tube, are angularly deflected both horizontally and vertically to scan a raster and having field-producing means adjacent to said predeflection paths and energizable to effect substantial convergence of said beam components at all points of said raster, a system to energize said field-producing means comprising, a source of a substantially sawtooth raster-scanning deflection wave, a convergence control wave-shaping network including two predominantly resistive branches, an electron tube having an input circuit and an output circuit, means coupled between said sawtooth wave source and said input circuit to impress a predetermined portion of said deflection wave upon said tube, said electron tube being operated in such a manner as to produce in said output circuit a first constituent sawtooth wave of predetermined polarity and generally similar in shape to said deflection wave, means coupling said output circuit to said wave-shaping

network in a manner to impress said first constituent sawtooth wave upon respective points of said resistive branches, means coupled to said deflection wave source to produce a second constituent sawtooth wave similar in shape to said first constituent sawtooth wave but of opposite polarity, means coupling said second constituent sawtooth wave-producing means to said wave-shaping network in a manner to impress said second constituent sawtooth wave upon other respective points of said resistive branches, means coupled between still other points of said resistive branches in a manner to integrate one of said constituent sawtooth waves into a substantially parabolic waveform, and means coupled to said integrating means to derive therefrom said convergence control wave for application to said field-producing means.

5. In a cathode ray image reproducing system wherein a plurality of electron beam components, which traverse predeflection paths that are spaced respectively about the longitudinal axis of a tube, are angularly deflected both horizontally and vertically to scan a raster and having field-producing means adjacent to said predeflection paths and energizable to effect substantial convergence of said beam components at all points of said raster, a system to energize said field-producing means comprising, a source of a substantially sawtooth raster-scanning deflection wave having a peaking component, a convergence control wave-shaping network including two resistive branches, an electron tube having an input circuit and an output circuit, voltage dividing means coupled between said sawtooth wave source and said input circuit to impress a predetermined portion of said deflection wave upon said tube, said electron tube being operated in such a manner as to produce in said output circuit a first reformed sawtooth wave of predetermined polarity and generally similar in shape to said deflection wave with said peaking component removed, means coupling said output circuit to said wave-shaping network in a manner to impress said first reformed sawtooth wave upon corresponding points of said resistive branches, means comprising a clipping circuit including a uni-laterally conducting device coupled to said deflection wave source to remove said peaking component from said deflection wave whereby to produce a second reformed sawtooth wave similar in shape to said first reformed sawtooth wave but of opposite polarity, means coupling said clipping circuit to said wave-shaping network in a manner to impress said second reformed sawtooth wave upon other corresponding points of said resistive branches, means coupled between points of said respective resistive branches in a manner to integrate one of said reformed sawtooth waves into a substantially parabolic waveform, and means coupled to said integrating means to derive therefrom said convergence control wave for application to said field-producing means.

6. In a cathode ray image reproducing system wherein a plurality of electron beam components, which traverse predeflection paths that are spaced respectively about the longitudinal axis of a tube, are angularly deflected both horizontally and vertically to scan a raster and having field-producing means adjacent to said predeflection paths and energizable to effect substantial convergence of said beam components at all points of said raster, a system to energize said field-producing means comprising, a source of a substantially sawtooth raster-scanning deflection wave having a peaking component, a convergence control wave-shaping network including two parallel-connected resistive branches, an electron tube having an input circuit and an output circuit, means including a voltage divider coupled between said sawtooth wave source and said input circuit to impress a predetermined portion of said deflection wave upon said tube, said electron tube being operated in such a manner as to produce in said output circuit a first reformed sawtooth wave of predetermined polarity and generally similar in shape to said deflection wave with said peaking component removed, means coupling said output circuit to one terminal of said wave-shaping

network to impress said first reformed sawtooth wave upon corresponding ends of said resistive branches, means including an output transformer coupled to said deflection wave source for impressing said deflection wave upon said raster-scanning deflection apparatus, means comprising a clipping circuit including a unilaterally conducting device and a resistive-capacitive network coupled to said deflection output transformer to remove said peaking component from said deflection wave whereby to produce a second reformed sawtooth wave similar in shape to said first reformed sawtooth wave but of opposite polarity, means coupling said clipping circuit to the other terminal of said wave-shaping network to impress said second reformed sawtooth wave upon the other corresponding ends of said resistive branches, means including an integrating network coupled between points of said respective resistive branches to integrate one of said reformed sawtooth waves into a substantially parabolic waveform, and means coupled to said integrating network to derive therefrom said convergence control wave for application to said field-producing means.

7. In a cathode ray image reproducing system wherein a plurality of electron beam components, which traverse predeflection paths that are spaced respectively about the longitudinal axis of a tube, are angularly deflected both horizontally and vertically to scan a raster and having field-producing means adjacent to said predeflection paths and energizable to effect substantial convergence of said beam components at all points of said raster, a system to energize said field-producing means comprising, a source of a substantially sawtooth raster-scanning deflection wave having a peaking component, a convergence control wave-shaping network including two parallel-connected branches, each including a potentiometer, an electron tube having an input circuit and an output circuit, means including a capacity voltage divider coupled between said sawtooth wave source and said input circuit to impress a predetermined portion of said deflection wave upon said tube, said electron tube being operated in such a manner as to produce in said output circuit a first reformed sawtooth wave of predetermined polarity and generally similar in shape to said deflection wave with said peaking component removed, means coupling said output circuit to one terminal of said wave-shaping

network to impress said first reformed sawtooth wave upon corresponding ends of said potentiometers, means including an output transformer coupled to said deflection wave source for impressing said deflection wave upon said raster-scanning deflection apparatus, means comprising a clipping circuit including a crystal diode and a resistive-capacitive network coupled to said deflection output transformer to remove said peaking component from said deflection wave whereby to produce a second reformed sawtooth wave similar in shape to said first reformed sawtooth wave but of opposite polarity, means coupling said clipping circuit to the other terminal of said wave-shaping network to impress said second reformed sawtooth wave upon the other corresponding ends of said potentiometers, means including a resistive-capacitive integrating network coupled between said potentiometers to integrate one of said reformed sawtooth waves into a substantially parabolic waveform, and means coupled to said integrating network to derive therefrom said convergence control wave for application to said field-producing means.

8. A convergence control wave-generating system as defined in claim 7 wherein, the peaking component of said deflection wave has a negative-going polarity, and said crystal diode is serially connected in said tube output circuit.

9. A convergence control wave-generating system as defined in claim 7 wherein, said integrating network includes a series arrangement of a resistor and a capacitor, said resistor being connected to the adjustable contact of one of said potentiometers, the adjustment of said one potentiometer contact determining the amplitude of said convergence control wave, and said capacitor being connected to the adjustable contact of the other of said potentiometers, the adjustment of said other potentiometer determining the amplitude and polarity of any sawtooth wave component combined with said parabolic wave to form said convergence control wave.
